PAUL RIESS, OF NEW ORLEANS, LOUISIANA, ASSIGNOR, BY DIRECT AND MESNE ASSIGNMENTS, TO STANDARD DEVELOPMENT COMPANY, LIMITED, OF NEW ORLEANS, LOUISIANA.

GAS-CHECK.

SPECIFICATION forming part of Letters Patent No. 792,928, dated June 20, 1905.

Application filed September 12, 1903. Serial No. 172,920.

To all whom it may concern:

Be it known that I, PAUL RIESS, a citizen of the United States, and a resident of New Orleans, in the parish of Orleans and State of Louisiana, have invented new and useful Improvements in Gas-Checks, of which the following is a full, clear, and exact description.

My invention relates to certain novel and useful improvements in gas-checks, and has particular application to a rotary approximately cylindrical check designed to be interposed between a gas meter and a burner for the purpose of regulating the flow of gas from the meter to the burner.

15 A further object of my invention is to provide an improved casing having therein a rotary approximately cylindrical valve or plug having a plurality of apertures or orifices through which gas may pass to the burner-pipe, said check being rotated to bring a desired number of apertures into line with the burner-pipe to permit the passage of a certain amount of gas therethrough for lighting, cooking, or heating purposes.

20 25 A further object of my invention is to provide an improved check having perforations or gas-openings therein for the passage of gas, the plug breaking or retarding the pressure of the gas passing through the gas-pipe or gas-main.

A further object of the invention is to provide a gas check or economizer which will embody the desirable and essential features of simplicity, durability, and economy.

30 35 With the above-recited objects and others of a similar nature in view the invention consists in the construction, combination, and arrangement of parts, as illustrated in the accompanying drawings, described in this specification, and set forth in the appended claims.

Reference is to be had to the accompanying drawings, forming a part of this specification, in which similar characters of reference indicate corresponding parts in all the figures.

40 45 Figure 1 is a perspective view of a device embodying my improvements. Fig. 2 is a vertical sectional view taken through the same. Fig. 3 is a perspective view of the ro-

tary gas valve or plug, and Figs. 4 and 5 are modified forms of my improved plug-valve. 50

Referring now to the accompanying drawings in detail, 5 designates the casing of my improvement having a gas-inlet 6 and a gas-outlet 6^a, the gas-inlet being a short tubular extension designed to be connected, through 55 the medium of a coupling-collar 7, with a pipe 8, leading from a source of gas-supply. The tubular extension 6 is preferably formed integral with the casing and is flared at 9 at the point of communication with said casing, so 60 that as the gas enters from the extension it will be permitted to spread. The casing is preferably of cylindrical form and is designed to have inserted therein a rotary plug or valve 10, (clearly shown in Fig. 3,) said valve having 65 at one of its free end faces 11 a stud 12, designed when the plug is in the casing to pass through a bore 13 in the end of the casing, said stud 12 forming an axis upon which the cylindrical plug or valve may be turned with- 70 in the casing. The opposite flat face 14 of the cylindrical valve-plug is in the nature of a flange of a greater diameter than the body portion of the plug, said flange being designed to rest against the opposite face of the 75 casing from that having therein the aperture for the passage of the stud 12. This flanged-face portion of the valve-plug is provided with a groove 15, designed to seat the pivoted handle 16, said handle being designed to be 80 brought at approximately right angles to the face for the purpose of turning the valve, and when the valve has been so rotated such handle may be folded down into the groove 15, so that the cap or cover 17, which is pivoted 85 at 18 to the side of the casing, may be swung over to conceal the flanged face of the plug. This cover portion 17 is provided with a slotted tongue 19, designed to engage with a locking-pin 20, mounted on the side of the casing to 90 lock the cover against movement when it has been moved to its closed position, the cover being loosely mounted on the pivot 18, so that the slotted tongue may be slipped over and into engagement with the relatively short pin 20. 95 The cylindrical valve-plug 10 is provided

circumferentially, approximately centrally of its curved surface, with series of openings 22, spaced apart, each series being made up of small perforations 23. The perforations of each series differ—that is to say, while one has two perforations that of the adjacent series will have three perforations, and so on up to a desired number. On the flanged face of the valve-plug are numerals, such as shown at 10 24 in Fig. 1, such numerals indicating the number of small perforations 23 in the series directly in line with such number. For instance, the numeral "2" upon the flanged face in Fig. 1, indicates that the series having two 15 perforations therein is presented to the gas-outlet leading to the burner. The curved wall of the plug has also formed therein additional apertures 25, preferably arranged in pairs, each pair being in line with one of the groups 20 of openings 22, the purpose of these apertures being to permit the ready flow of gas from the flared portion 9 of the tubular extension 6 into the valve-plug, thereby equalizing pressure in the device, gas passing freely through 25 these large apertures into the plug-valve, where it is accumulated and held as a check, so that only the required amount is fed into the supply-pipe through the different series of small perforations.

30 In Figs. 4 and 5 I have shown slightly-modified forms of the plug-valve. In Fig. 4 I have connected all the series of apertures 23^a with a groove 26^a, which is formed in the plug and extends circumferentially thereof, the openings 25^a being arranged in longitudinal alinement with the apertures 23^a, while in Fig. 5 the openings 25^b are arranged in transverse alinement with the series of apertures 23^b and are connected therewith by the circumferential groove 26^b. The purpose of the groove is to enable the valve to be turned to increase or decrease the supply of gas while the lights are burning without cutting said supply off entirely and extinguishing the lights.

40 It will be noted that I have provided a device which may be readily applied to the existing systems of gas-piping in residences, offices, and the like and one which will effect a great saving in the amount of gas consumed, 45 as it obviates the objection of consuming more gas than is required at the time.

Having thus described my invention, I claim as new and desire to secure by Letters Patent—

1. A gas-check, comprising a casing having 50 an inlet and outlet, and a hollow cylindrical valve-plug mounted to turn in the casing in contact therewith, said plug being provided with sets of openings arranged at about the center of length of the plug and adapted to 55 be brought into alinement with the outlet of the casing, and openings of larger diameter than the openings of the sets and adapted to be brought into alinement with the inlet of the casing, the sets of openings being spaced apart and each formed of a plurality of open-

ings, the openings of the several sets varying in number, as set forth.

2. A gas-check, comprising a casing having an inlet and outlet, and a hollow cylindrical valve-plug mounted to turn in the casing in contact with the inner surface thereof, said plug being provided with openings adapted to be brought into alinement with the inlet of the casing and with sets of openings spaced apart and arranged at about the center of length of the plug, and in alinement with the first-named openings, said sets of openings being adapted to be brought into alinement with the outlet of said casing and a circumferential groove connecting the sets of openings, the sets of 75 openings being each formed of a plurality of openings and the openings in the sets varying in number, as set forth.

3. A gas-check, comprising a casing having an inlet and outlet, and a hollow cylindrical valve-plug having a flange at one end and mounted to turn in the casing in contact with the inner surface thereof, said plug being provided with sets of openings adapted to be brought into alinement with the outlet of the casing, a circumferential groove connecting the sets of openings, and openings of larger diameter than the openings of the sets, and arranged in alinement with the said sets of openings, the said larger openings being adapted to be brought in alinement with the inlet of the valve-casing, the sets of openings being spaced apart and the openings of the sets varying in number, as set forth.

4. A gas-check, consisting of a casing having an inlet and outlet, and provided with a pivoted cover, and a hollow cylindrical valve-plug having at one end a flange upon which is mounted a folding handle, said plug being mounted to turn in the casing with its flange 100 engaging the end of the casing and provided with sets of openings adapted to be brought into alinement with the outlet of the casing, a circumferential groove connecting the sets of 105 openings, and openings arranged in alinement with the sets of openings and adapted to be brought into alinement with the inlet of the casing, the sets of openings being spaced apart and the openings of the sets varying in number, as set forth.

5. A gas-check, comprising a casing having an inlet and outlet, and a hollow cylindrical valve-plug mounted to turn in the casing and provided with sets of openings, the sets of 110 openings being spaced apart and each formed of a plurality of openings, the openings of the sets varying in number openings of larger diameter than the openings of the sets and arranged in transverse alinement therewith, and a circumferential groove connecting the larger 115 openings with the sets of openings, as set forth.

6. A gas-check, comprising a cylindrical casing open at one end and having an inlet and outlet, the inlet being flared at the point of communication with the casing, and a hol- 120 125 130

low cylindrical valve-plug having a flange at one end and mounted to turn in the casing with the flange engaging the open end of the casing, said plug being provided with sets of 5 openings spaced apart and arranged at about the center of length of the plug, each set being formed of a plurality of openings, the openings of the sets varying in number, and with openings larger than the openings of the

sets and arranged in alinement therewith, as 10 set forth.

In testimony whereof I have signed my name to this specification in the presence of two subscribing witnesses.

PAUL RIESS.
